UNITED STATES PATENT OFFICE

114,693

DESIGN FOR A WOODEN CHAIR

Clarence Hudson Wood, South Lancaster, Mass.

Application March 11, 1939, Serial No. 83,527

Term of patent 7 years

To all whom it may concern:

Be it known that I, Clarence Hudson Wood, a citizen of the United States, residing at South Lancaster, in the county of Worcester and State of Massachusetts, have invented a new, original, and ornamental Design for a Wooden Chair, of which the following is a specification, reference being had to the accompanying drawing, forming part thereof.

The figure is a perspective view of a wooden chair, showing my new design.

I claim:

The ornamental design for a wooden chair, as shown.

CLARENCE HUDSON WOOD.
